UNITED STATES PATENT OFFICE.

SAMUEL E. RAHE, OF NEW YORK, N. Y., ASSIGNOR TO RAHE MATCH COMPANY, OF NEW YORK, N. Y., A CORPORATION.

MATCH-MAKING MACHINE.

1,030,790.

Specification of Letters Patent. Patented June 25, 1912.

Application filed May 23, 1911. Serial No. 629,072.

To all whom it may concern:

Be it known that I, SAMUEL E. RAHE, a citizen of the United States, and a resident of the city of New York, borough of Brooklyn, in the county of Kings and State of New York, have invented a new and Improved Match-Making Machine, of which the following is a full, clear, and exact description.

10 The invention relates to match-making machines having an endless chain of carrier plates for receiving the splints and carrying the same from device to device for automatically completing the matches and 15 finally ejecting the same.

The object of the invention is to provide a new and improved match-making machine, provided with a splint-filling device for the outgoing portion of the endless 20 chain of carrier plates, and a match-ejecting device for the return portion of the endless chain of carrier plates, and a single intermittently-driven gear wheel in mesh at opposite sides with the outgoing and return 25 portions of the said endless chain of carrier plates to impart an intermittent traveling motion to the same.

A practical embodiment of the invention is represented in the accompanying drawings forming a part of this specification, in which similar characters of reference indicate corresponding parts in all the views.

Figure 1 is a side elevation of the match-making machine; Fig. 2 is a sectional front view of the same on the line 2—2 of Fig. 6; Fig. 3 is an enlarged sectional elevation of the splint-filling device and showing more particularly the means for cleaning the splint-carrying slide; Fig. 4 is a similar 40 view of the same with the parts in a different position; Fig. 5 is a cross section of the same on the line 5—5 of Fig. 4; Fig. 6 is an elevation of one side of the match-making machine; Fig. 7 is a face view of one of the 45 pin wheels; Fig. 8 is a cross section of the same on the line 8—8 of Fig. 7; Fig. 9 is a face view of the match-ejecting device; Fig. 10 is a cross section of the same on the line 10—10 of Fig. 9; and Fig. 11 is a plan view 50 of the lower section of the hopper.

On a suitably constructed frame A is journaled a shaft B carrying mutilated gear wheels C in mesh at diametrically opposite points with toothed racks D' forming

part of an endless chain of carrier plates D 55 for receiving the splints, as hereinafter more fully explained, the toothed racks being connected with each other by hinge joints D², as plainly indicated in Figs. 1 and 2. When the mutilated gear wheel C 60 is rotated in the direction of the arrow a then a traveling motion is given to the endless chain of carrier plates D, in such a manner that the outgoing portion on the right-hand side of the mutilated gear wheel 65 C travels in the direction of the arrow b, while the return portion of the endless chain of carrier plates on the left-hand side of the mutilated gear wheel C travels in the direction of the arrow b'. The splint delivery or filling device E is located on the right-hand side of the machine for filling the splints into the outgoing portion of the endless chain of carrier plates, and the match-ejecting device F is arranged on the left-hand side of the machine to eject the finished matches from the plates on the return portion of the endless chain of carrier plates. The mutilated gear wheels C are in mesh 70 with corresponding pinions G, secured on a shaft H journaled in suitable bearings on the main frame A, and on the ends of the shaft H are secured pin wheels I and J, adapted to be engaged by cams K and K' secured on cam shafts K², K³, of which 75 the shaft K² is provided with a pulley K connected by a belt with other machinery for imparting a rotary motion to the cam shaft K². On the cam shaft K² is secured a bevel gear wheel K⁴ in 80 mesh with a bevel gear wheel K⁵ secured on a shaft K⁶ journaled on the main frame A. On the shaft K⁶ is secured a bevel gear wheel K⁷ in mesh with a bevel gear wheel K⁸ secured on the cam shaft K³, so that 85 when the cam shaft K² is rotated, a like rotary motion is given to the cam shaft K³ by the gearing just described. The cam K is a slow-pitch cam and acts on two sets of pins I' formed on the face of the pin wheel 90 I, the sets of pins being spaced apart and each set containing as many pins as there are teeth in a toothed rack D' and the corresponding set of teeth C' on the mutilated gear wheel C. The cam K' is a quick-pitch 95 cam and is adapted to engage two diametrically opposite pins J' arranged on the face of the pin wheel J, the said pins J' be-

ing disposed in a transverse plane passing through the spaces between the two sets of pins I' on the pin wheel I . Now when the machine is running, the cam K acts successively on the pins I' of a set, to turn the mutilated gear wheel C while in mesh with the corresponding toothed rack L' , and when the mutilated gear wheel reaches a hinge joint D^2 then the other quick-pitch 10 cam K' acts on a corresponding pin J' to turn the mutilated gear wheel C while passing the hinge joint D^2 .

In practice, the cam K' turns the wheel C at double the speed of the cam K , and 15 hence the motion given to the endless chain of the carrier plates D is uniform. It is understood that on one revolution of the shaft K^2 , the slow-pitch cam K causes a 20 turning of the gear wheel C a distance corresponding to the distance between two teeth of the gear wheel C , and when the cam K has passed the last pin of a set of pins I' then this cam K does not act further on the pin wheel during the next revolution of the shaft K^2 , but the quick-pitch 25 cam K' during this revolution acts on the corresponding pin J' of the pin wheel J to advance the gear wheel C the distance between adjacent toothed portions of the wheel 30 C , and which distance corresponds to the distance of two teeth of the wheel C . Thus a uniform step by step movement interrupted at intervals by accelerated movement is given to the endless chain of carrier plates 35 D at each revolution of the shaft K^2 .

The splint-filling device E for filling the splints into the perforations D^3 of the carrier plates D is arranged as follows: The delivery or setting slide E' is mounted to 40 slide on top of a guideway A' , attached to or forming part of the main frame A (see Fig. 2), and the said delivery or setting slide E' is provided with grooves of different depth to accommodate two rows of superposed splints at the time, the said slide E' being preferably of the construction shown and described in the Letters Patent for a match making machine, No. 951,381, granted to me on March 8, 1910, so that further 45 detailed description of the said slide is not deemed necessary, it being understood that with the slide E' operates a bar E^2 having depending tongues extending into the grooves of the slide E' in such a manner as 50 to leave sufficient space in each of the grooves for the discharge of a single splint. The slide E' is connected by outwardly-extending rods E^3 with a cross head E^4 mounted to slide in suitable bearings A^2 attached to 55 or formed on the main frame A , and the ends E^5 of the cross head E^4 are connected by pitmen L , L' with crank wheels L^2 , L^3 secured on the ends of a shaft L^4 journaled in suitable bearings on the main frame A . 60 The crank wheel L^2 is in the form of a

sprocket wheel connected by a sprocket chain L^5 with a sprocket wheel L^6 secured on the shaft K^6 , so that when the machine is running and the said shaft K^6 is rotated, then a rotary motion is transmitted by the 70 sprocket wheel L^6 , chain L^5 and wheel L^2 to the shaft L^4 , whereby both pitmen L and L' impart reciprocating motion to the slide E' to move the same toward and from the carrier plate D in active position at the filling 75 device E .

Above the slide E' , when in a rearmost position, is arranged a hopper N having a fixed upper portion N' and a reciprocating lower portion N^2 provided with a number of partitions N^3 which serve to maintain the splints in parallelism and at the same time agitate the entire mass of splints so as to prevent their sticking or clinging to the hopper. 80

It is understood that the splints pass from the lower hopper section N^2 into the grooves of the slide E' , one splint filling a groove at a time. The lower hopper section N^2 is connected by a pitman N^4 with a crank wheel N^5 secured on a shaft N^6 journaled on the main frame A and carrying a sprocket wheel N^7 connected by a sprocket chain N^8 with a sprocket wheel N^9 fastened on the cam shaft K^3 . Thus when the machine is running and 90 the cam shaft K^3 is rotated then a reciprocating movement is given to the lower hopper section N^2 by the mechanism described and for the purpose above set forth. 95

In order to hold the splints against upward movement while the slide E' moves the same into engagement with the perforations D^3 of a carrier plate D and to clean the grooves of splints or other extraneous matter, use is made of a comb O having 100 teeth normally standing directly above the splints at the time the slide E' moves into forward position, as indicated in Fig. 3, so that the splints are readily pushed by the slide E' into the perforations D^3 . When the 105 slide E' recedes the comb O moves downward, so that its teeth pass into the grooves of the slides E' , and during the further return or outward movement of the slide E' the teeth are in the grooves and consequently 110 many splints or other matter in the grooves are pushed out of the same by the teeth of the comb O . The comb O is provided on its upper end with pins O' extending through elongated slots A^3 formed in the main frame 115 A (see Fig. 2), and the outer ends of the pins O' are engaged by arms P attached to levers P' fulcrumed at P^2 on the bracket P^3 attached to the main frame A . The levers P' are provided with friction rollers P^4 , of 120 which one travels on the peripheral face of the wheel L^3 previously mentioned, while the other friction roller travels on the face of a similar wheel P^5 secured on the shaft L^4 , the said wheels L^3 and P^5 being provided 125

with cut-out portions for imparting an intermittent up and down sliding motion to the comb O. It is understood that during the movement of the slide E' toward the carrier plate D, the comb O is on top of the splints held in the grooves of the slide E', and after the splints are pushed into final position in the carrier plate D then the comb O is in the rear of the splints, and 5 immediately after the slide E' starts on the return or outward stroke, then the comb O moves downward into the grooves of the slide E' in the rear of the splints, and consequently any extraneous matter that is contained in the grooves of the slide E' is pushed out during the return outward movement of the slide E'. By having the comb O directly above the outer ends of the splints at the time of forcing the inner ends 10 into the perforations D^a, the splints are not liable to leave the grooves in the slide E' in case the splints are slightly eccentric and not in absolutely accurate alignment relative to the perforations D^a.

25 The ejecting device F is constructed as follows, special reference being had to Figs. 9 and 10: Punches F' are arranged in rows corresponding to the perforations D^a in the carrier plates D, and the said punches are 30 clamped between bars F², F³, F⁴, of which the bar F² forms an integral part of a punch holder frame F⁵, while the bars F³ and F⁴ are loose in the said frame and are engaged by screws F⁶ screwing in the top and bottom 35 of the frame F⁵ against the bars F³, F⁴, to securely clamp the punches F' against the middle bar F². The back of the frame F⁵ is provided with apertures F⁷ to permit of conveniently removing and replacing the 40 punches F' in case such punches are worn out or broken, it being understood that for removing a punch and replacing the same by a new one, it is only necessary to loosen the corresponding screws F⁶ and force the 45 worn out punch rearwardly through the opening F⁷ and re-insert a new punch through the said opening, after which the grooves F⁶ are again screwed up to clamp the punches in place. The holder frame F⁵ 50 is attached to brackets Q secured to a bar Q' mounted to slide on bearings A⁴ on the main frame A, and the said bar Q' is provided with a depending open bearing Q² engaged by the upper end R' of a rocking lever R, 55 fulcrumed at R² on the main shaft frame A. The lower end of the rocking lever R is in the form of a fork R³ engaged by an eccentric R⁴ secured on the shaft K⁶, so that when the machine is running a rocking motion is 60 given to the lever R to reciprocate the ejecting device F with a view to cause the punches F' to force the matches out of the perforations D^a of the carrier plate D. The carrier plates D are guided on the return 65 side of the frame on guideways S attached

to the main frame A, and the ejected matches drop down into a chute T for setting the matches to one side of the machine.

The pin wheels I and J are alike in construction except the arrangements of their pins I' and J', and each is constructed as follows, special reference being had to Figs. 7 and 8, which show in detail the pin wheel J. The pin wheel J is formed of two disks J², J³, fastened together by screws J⁴, screwing in the front disk J³ and extending through elongated slots J⁵ formed in the disk J². Thus on loosening the screws J⁴, the disk J³ can be turned on the disk J², so as to bring the pins J' in proper position relative to the cam K', and when the desired adjustment is made, the screws J⁴ are screwed up to securely fasten the disks together. The disk J² is secured to the shaft H. The disk J² is provided on its face with annular grooves J⁶, into which fits a correspondingly-shaped annular rib J⁷ to hold the disks J² and J³ against lateral shifting one on the other. It is understood that the pin wheel I is constructed in a like manner, 90 that is, of two sections adjustably fastened together by screws, as described relative to the pin wheel J.

The operation is as follows: When the machine is running, a step by step movement, interrupted at intervals by accelerated movement, is given to the endless chain of carrier plates D, in such a manner that the outgoing portion thereof travels upward at the splint-filling device E, while the incoming portion travels downward at the ejecting device F. The splint-filling device E pushes two rows of splints into corresponding rows of apertures D^a of the carrier plate D at rest at the time, and at the same time the punches F' eject two rows of matches from the corresponding plate D at the ejecting side of the machine. During the inward movement of the slide E' of the filling device E, the comb O prevents the splints from upward movement in the slide E' at the time the latter enters the forward ends of the splints into the perforations D^a, and after the splints have been pushed into the perforations D^a to the full depth thereof, 110 then the comb O is slightly in the rear of the outer ends of the splints, and when the slide E' now recedes or moves outward then the comb O descends and its teeth pass into the grooves of the slide E' to clean the same of extraneous matter during the further return movement of the slide E', and prior to the slide E' reaching the end of its outward stroke the comb O moves upward to its position of rest; and a new batch of splints now 120 fills the grooves of the slide E' from the lower shaking section N² of the hopper N. During the return movement of the slide E' movement is given to the endless chain of carrier plates D, which again come to rest 130

at the next forward movement of the slide E', when the above-described operation is repeated on the filling side of the machine. On the ejecting side of the machine, the 5 lever R imparts an outward reciprocating motion to the bar Q' and the parts carried thereby, so that the punches F' engage the matches from the inner face of the carrier plate D at rest at the time, and push the 10 said matches out of the perforations D', and during the return movement of the bar Q' the endless chain of carrier plates D moves to the next position, and the above described operation is repeated.

15 It is understood that the filling device E and the ejecting device F are actuated in unison, one for filling the carrier plates with splints and the other for ejecting the matches from the returning carrier plates.

20 Having thus described my invention, I claim as new and desire to secure by Letters Patent:

1. In a match-making machine having an endless chain of carrier plates and a slotted 25 frame, a reciprocating delivery slide provided with grooves for the splints, and a reciprocating cleaning comb having its teeth extending over the rear ends of the splints at the time the forward ends of the splints 30 enter the said plates, said comb having pins extending into the frame slots, arms connected to the pins, and rocking levers engaging the arms to cause the said comb to move into the grooves on the receding of the 35 slide to clean the grooves.

2. In a match-making machine having an endless chain of carrier plates, a reciprocating ejecting device having punches, punch holder frame, a series of clamping bars held 40 one above the other and bearing against opposite sides of a portion of the said holder frame, and between which bars and said frame portion the punches are clamped, and screws on the said holder frame engaging 45 the top and bottom bars.

3. In a match-making machine having an endless chain of carrier plates, a reciprocating ejecting device having punches, a punch holder frame provided at its back with ap-

ertures in alignment with the said punches, 50 a series of clamping bars held one above the other and bearing against opposite sides of a portion of the said holder frame and between which bars and said frame portion the punches are clamped, and screws on the 55 said holder frame engaging the top and bottom bars.

4. In a match-making machine having an endless chain of carrier plates, a reciprocating ejecting device having punches, a punch 60 holder frame, a series of clamping bars held one above the other and bearing against opposite sides of a portion of the said holder frame and between which bars and said frame portion the punches are clamped, 65 screws on the said holder frame engaging the top and bottom bars, supporting brackets for the said punch holder frame, a bar carrying the said brackets and provided with a bearing, and a rocking lever engaging the said bearing for imparting a reciprocating motion to the said bar and the parts carried thereby.

5. In a match-making machine having an endless chain of carrier plates provided with 75 toothed racks and hinge joints, a driven shaft, a quick pitch cam thereon, a shaft parallel with said driven shaft and connected therewith in spaced relation, a slow pitch cam on said last named shaft, upper and 80 lower shafts in the same vertical plane, both arranged above and at right angles to said first named shafts, pin wheels mounted on the lower of said last named shafts and adjacent their respective cams, and mutilated 85 gears connecting said upper and lower shafts, the gear wheel of the upper shaft being enlarged and extending between the sides of the said endless chain of carrier plates to engage on opposite sides the out- 90 going and return portions of said chain.

In testimony whereof I have signed my name to this specification in the presence of two subscribing witnesses.

SAMUEL E. RAHE.
